UNITED STATES PATENT OFFICE.

CHARLES A. SEE, OF CHICAGO, ILLINOIS.

PENCIL-EXTENDER.

945,617.

Specification of Letters Patent. Patented Jan. 4, 1910.

Application filed May 3, 1909. Serial No. 493,494.

To all whom it may concern:

Be it known that I, CHARLES A. SEE, a citizen of the United States, residing at Chicago, in the county of Cook and State of Illinois, have invented certain new and useful Improvements in Pencil-Extenders, of which the following is a specification.

This invention relates to improvements in a device to be used as a holder, extender and protector for pencils, and especially for lead pencils; and it consists in certain peculiarities of the construction, novel arrangement, and operation of the parts thereof, as will be hereinafter more fully set forth and specifically claimed.

The principal object of the invention is to provide a pencil extender, holder and protector, which shall be simple and inexpensive in construction, strong, durable and effective in operation, and so made that it will be adapted for pencils of different sizes and will firmly hold them in position for use or with their points protected.

A further object of the invention is to so construct the device that it may be used as an advertising medium, or, in other words, may have advertising matter displayed on its external surface.

Other objects and advantages of the invention will be disclosed in the subjoined description and explanation.

In order to enable others skilled in the art to which my invention pertains, to make and use the same, I will now proceed to describe it, referring to the accompanying drawing, in which—

Figure 1 is a perspective view of a pencil extender, holder and protector embodying one form of the invention, showing a short piece of pencil in position thereon for use; Fig. 2 is a view in side elevation of the extender or holder; and Fig. 3 is a face view of the blank out of which the device is formed.

Like numerals of reference, refer to corresponding parts throughout the different views of the drawing.

Referring now to Figs. 1 to 3, inclusive, of the drawing, the device is made of a single piece 7 of material, preferably metal, which, in its blank form, is of substantially

the shape shown in Fig. 3 of the drawing. The piece 7 is rolled or bent into tubular form to form the extender or holder, which is designated as a whole by the reference 55 numeral 8, which, as shown, in Figs. 1 and 2 consists of the central or body portion 9 and the slotted end-portions 10 and 11. The body portion 9 is divided by a spiral slot 12, which is extended longitudinally at each of 60 its ends as at 13 and 14 through the ends of the extender or holder, and are preferably located out of alinement with one another, as is clearly shown in Fig. 1 of the drawing. The spiral slot 12 of the central or body 65 portion 9 is formed by the diagonally disposed edges 15 of the blank piece 7 while the slots 13 and 14 are formed by the longitudinally disposed edges 16 and 17, respectively, of the piece 7 which, as before stated, 70 is bent or rolled up so that said edges will approximate each other, thus forming a tubular member having a slot throughout its entire length, but longitudinally thereof at each of its ends, yet spirally with respect 75 thereto between its ends. By thus forming the piece 7 it is apparent that a torsion spring-clamp of great resiliency and tension will be afforded, into either or both ends of which pencils or short pieces thereof 80 may be readily inserted and firmly held in place with the points exposed for use or, if desired, said points may be inserted inwardly into the device when they will be protected thereby.

Having thus fully described my invention, what I claim as new, and desire to secure by Letters-Patent, is—

A pencil extender or holder consisting of a single piece having end-portions out of 90 alinement with one another and each provided with parallel side edges and a central portion connecting said end parts and having parallel side edges disposed diagonally with respect to the end-portions, said piece 95 bent spirally until its side edges are approximated and thereby formed into a torsion spring-clamp.

CHARLES A. SEE.
